(57) **CLAIM**

The ornamental design for a facade for a canned pet food dispenser, as shown and described.

DESCRIPTION

FIG. 1 is a perspective view of the facade for a canned pet food dispenser of the invention in place on the front of a rack used for dispensing cans, the rack being shown in phantom lines as not forming a part of the invention;

FIG. 2 is a close-up view of the facade for a canned pet food dispenser of the invention showing the facade in greater detail, portions of the associated rack again being shown in phantom lines;

FIG. 3 is a front plan view of the facade for a canned pet food dispenser of the invention;

FIG. 4 is a left side view of the facade of FIG. 3;

FIG. 5 is a right side view of the facade of FIG. 3;

FIG. 6 is a back view of the facade of FIG. 3;

FIG. 7 is a top view of the facade of the invention; and,

FIG. 8 is a bottom view of the facade of the invention.
